[57] CLAIM

The ornamental design for a drum storage container, as
shown and described.

DESCRIPTION

FIG. 1 is a front perspective view of a drum storage
container, showing our new design the door shown partially
raised;

FIG. 2 is a top view thereof;

FIG. 3 is a rear elevational view thereof;

FIG. 4 is a left side elevational view, the right side eleva-
tional view being a mirror image thereof; and,

FIG. 5 is a front perspective view showing the interior of the
drum storage container according to our new design the door
shown fully raised.

The broken lines are for illustrative purposes only and form
no part of the claimed design.
